UNITED STATES PATENT OFFICE

154,482

DESIGN FOR A HUNTING KNIFE

Emil H. Hill, Chicago, Ill.

Application December 12, 1946, Serial No. 135,450

Term of patent 14 years

(Cl. D22—3)

To all whom it may concern:

Be it known that I, Emil H. Hill, a citizen of the United States, residing at 845 West Newport Avenue, in the county of Cook and State of Illinois, have invented a new, original, and ornamental Design for Hunting Knives, of which the following is a specification, reference being had to the accompanying drawing, forming a part thereof, and in which:

Figure 1 is a side elevation of the hunting knife, showing my new design when in operative position;

Figure 2 is a top plan view of Figure 1;

Figure 3 is an end elevation of the haft;

Figure 4 is a side elevation of the knife when the blade is in its inoperative position.

I claim:

The ornamental design for a hunting knife, substantially as shown and described.

EMIL H. HILL.
